Carpets

662

No 168.
Peter Lanson (Design for Carpetting) Oct 22, 1848.

Peter Lawson, Lowell Massachusetts,
Letters Patent No. 168 dated 22 February 1848

The Schedule referred to in these Letters Patent and
making part of the same.

To all to whom these presents shall come:

Be it known that I Peter Lawson, of Lowell, in the County of Middlesex and State of Massachusetts have invented or produced a new Design or figure to be woven into carpets and other fabrics and that the following is a full, clear, and exact description of the principle

Des. 668

2

or character which distinguishes it from all other things before known,
reference being had to the accompanying drawing, which forms a part of this
description and numbered 662.

The design consists of two principal figures, one of which is
an octagonal centre α surrounded by two bands of different figured ribbon
or scroll work δ twisted over a ruby ground; the ribbon being yellow
and white in the accompanying drawing; the outer border of the octagon
has each angle terminated with a leaf ϵ , and radial bars δ run from
the centre out to the other circumference between the angles. The other
principal figure is a square ϵ in outline, with the segments of a circlet
 δ scolloped out of each corner; the centre of this square is filled with
stripes, which in the drawing are yellow, shaded green, red and blue;
and over these stripes are drawn foliate work κ , portions of which ex-
tend over the border on to the ruby ground at eight points, or on each
side of each of the scollops abovesigned; each of the stripes κ has a
small figure on it, and between the sprigs of foliage on the straight
side of the square, there is a small die figure β ; in addition to the
above figures there is another small one formed of two flowers and
leaves i . It is obvious that some or all of these colours may be changed
without altering the figure, but the colours here produced I deem most
appropriate.

Therefore what I claim as my invention, and desire to secure
by letters patent, is the above described figure or design, and secondly,
the arrangement of colours in combination therewith.
